UNITED STATES PATENT OFFICE.

EDWIN M. BYRKIT, OF MICHIGAN CITY, ASSIGNOR OF THREE-FOURTHS TO ADDISON A. ADAIR, JOHN H. MURRY, AND HENRY COBURN, ALL OF INDIANAPOLIS, INDIANA.

SHEATHING AND LATH MACHINE.

SPECIFICATION forming part of Letters Patent No. 357,521, dated February 8, 1887.

Application filed July 14, 1886. Serial No. 207,960. (No model.)

To all whom it may concern:

Be it known that I, EDWIN M. BYRKIT, a resident of Michigan City, Indiana, have made certain new and useful Improvements in 5 Sheathing and Lath Machines, a description of which is set forth in the following specification, reference being made to the accompanying drawings, in the several figures of which like letters represent like parts.

10 My invention relates to the construction of machines for forming grooves and kerfs in boards intended to be used as sheathing and laths, and is an improvement upon the device shown in Letters Patent No. 335,335, issued to 15 me February 2, 1886, and will be understood from the following description.

In the drawings, Figure 1 represents a front view of the entire machine, the front portion of the frame-work being cut away so as to 20 show the relation of the operative parts. Fig. 2 is a longitudinal section of the adjustable mandrel which carries the grooving-saws. Fig. 3 is a side view of the same. Fig. 4 is a top view of the mandrel with its adjustable boxings that carry the lower series of saws which 25 cut the kerfs in the under side of the sheathing, a portion of the frame being shown in cross-section. Fig. 5 is a side view of a portion of the same mechanism, the saws and 30 driving-pulleys being left off. Fig. 6 is an end view of the same.

In detail, *f* is the frame-work, preferably made of iron, standing on four feet, the front portion of which is cut away so as to show 35 the operating mechanism of the machine, as set forth in Fig. 1. This front portion rests upon two legs similar to those shown in Fig. 1, and provides a broader support for the frame, and may be used, if desired, for carrying 40 the driving-pulleys, from which belts pass to the pulleys proper of the machine.

The frame-work *f* at its upper end provides bearings for the shaft *sh*, which carries beveled gears *g*, intermeshing with similar gears, *g'*, mounted on the upper end of the screws *sc*, 45 which pass through an upper supporting-bar, *b'*, and pass downward into the cross-piece *f'*, whose ends are grooved to slide upon the rounded faces of the frame-work, and by turning 50 the crank *c* the screws *sc*, which work in

the threaded openings near the ends of the cross-piece *f'*, will cause this cross-piece to rise or fall, according as the crank is turned, carrying with it the adjustable mandrels *m*, which are detachably fastened to each side of this cross-piece by means of the bolts *5*, passing through slots *6* into a boss or projection *b'* on the sides of the sleeves *sl*, which surround the mandrels. These mandrels are constructed in the manner shown and described in Letters Patent No. 60 335,335, issued to me on the 2d of February, 1886, and no claim is made separately thereon in this application. It is sufficient to say, by way of description generally, that the mandrels proper, *m* and *m'*, are surrounded by 65 boxings *b* and *b'*, within which the mandrels revolve, and these boxings by sleeves *sl* and *sl'*, which are constructed in halves, as shown in Figs. 2 and 3, and united by bolts, and by loosening these bolts the mandrels are adjustable along the line of their length in the boxings, and, when the proper length is determined, by tightening the bolts which unite the halves of the outer sleeve, the boxing is firmly clamped, but not so tightly as to prevent the mandrel from revolving therein. The mandrels *m* and their sleeve and boxings are attached to the cross-piece *f'* of the frame, and the lower mandrel is suspended in boxings 70 beneath the table *t*, as hereinafter described. The mandrels carrying the upper saws are placed one ahead of the other and on opposite sides of the cross-piece, so as to cut opposite sides of the dovetailed groove in the sheathing-lath *L*, as shown in Fig. 1. 75

l is a lug which projects from the cross-piece *f'*, and provides a bearing for the screw-rod *r*, which works in the threaded opening formed in a projection from the boss *b'*, and by tightening or loosening this screw it is obvious that 80 the mandrel is allowed a horizontal adjustment within the limits of the length of the long slot *6*, it being understood that a similar screw-rod is placed on each side of the cross-piece *f'* for each mandrel. This part of the 85 mechanism is fully shown and described in Letters Patent No. 335,335, before mentioned.

The sheathing-lath *L* is placed on a table, *t*, which extends across midway between the supports of the frame, and is suitably braced at 90 95 100

each end. The sheathing-lath L is placed about the center of this table, as shown in Fig. 1, and directly beneath it are openings in the table to allow the edges of the undercutting-saws s' to pass up through and project a sufficient distance above the top of the table to cut a series of kerfs of the proper depth in the under side of the sheathing-board, at the same time that the dovetailed grooves are being cut 5 in its upper surface by means of the saws mounted on the inclined mandrels. These undercutting-saws s' are mounted on a secondary mandrel, m', which has a bearing near its outer end in a movable block clamped to the 10 side of the frame f, and is supported near the other end in bearings in a hanger, h, which is bolted at 1 and 2 to the side of the table t. This hanger has upon its sides long slots which receive bolts 3 and 4, passing through the slots 15 into the sleeve s'. This mandrel m' is provided near each end with sleeves and bushing like those shown in the other mandrels, but somewhat shorter, there being a space left in the center between the bushings. The outer 20 end of the mandrel carries a driving-pulley, p', and has bearings in a movable block, 8, as shown in Fig. 6, which slides in guides 9 on each side, and is provided with slots 12 and 13, to receive clamping-screws 11, which secure 25 it to the frame-work f, through which the mandrel also passes.

s' is a lifting-screw which passes through the table t down into a shelf, 14, which has a threaded opening to receive the screw. This 30 shelf is secured to the sleeve s' of the mandrel, and also to the movable block 8, so that by loosening the clamp-screws 3 and 4 in the hanger h and 11 on the side of the frame, and turning the screw s' the mandrel m', with 35 its attachments, including the undercutting-saws, may be raised or lowered within proper limits, and the depth of cut of the saws may be increased or diminished at the pleasure of the operator.

40 o are oil-cups which connect by suitable pipes, such as p', with oil-boxes ob in the sleeves, through which openings extend to the mandrels, for the purpose of lubricating them.

br is a brace for connecting the sides of the 45 frame near the bottom, the frame being securely bolted to the floor or other foundation, through each foot, as shown in Fig. 1, and is thus made perfectly steady and secure.

I thus provide a combined machine carrying in the upper portion of its frame a series 50 of saws of different diameters mounted on oppositely-inclined mandrels, which are detachably secured to a cross-piece of the frame, which can be raised or lowered in a vertical 55 plane, while the mandrels themselves are adjustable in their sleeves along the line of their length and with their sleeves and boxes horizontally upon the cross-piece to which they are attached, and in the lower portion 60 of the frame, below the table upon which the material rests, I provide an adjustable

mandrel carrying a series of undercutting-saws which cut the kerfs in the block or board while the upper saws are cutting the dovetailed grooves in the face, and this undercutting mechanism is also adjustable horizontally and vertically, so that the depth of the cut may be regulated by the means hereinbefore described.

Having thus described my invention, what I 70 claim, and desire to secure by Letters Patent, is the following:

1. In a sheathing and lath machine, a series of saws mounted on a shaft beneath a table supported in the frame-work, for cutting kerfs 80 on the under side of a board, and a series of saws mounted on oppositely-inclined shafts above such table, for cutting a dovetailed groove in the upper side of the same board, these upper and under cutting saws located 85 substantially in the same vertical plane and operating concurrently, the board being firmly held between such saws, with mechanism for driving the same, all combined substantially as described. 90

2. In a sheathing and lath machine, a frame-work having a table upon which the material rests, a series of saws of different diameters removably mounted on mandrels oppositely inclined to each other and adjustably connected to a portion of the frame, so as to be raised or lowered by means of suitable screw-and-gear mechanism, a shaft beneath such table having a bearing at one end in a support movable vertically in the side of the frame, with means for securing the same at any desired point and supported near the center by means of a hanger, also allowing a vertical adjustment of such shaft, and a series of saws mounted upon such shaft at right angles 100 to its length and passing up through openings in the table to cut the kerf in the under side of the sheathing material, with suitable screw mechanism for lowering such undercutting-saws, all combined substantially as described. 105

3. A sawing-machine for operating on both sides of a board at once, comprising, in combination, a series of upper saws mounted on oppositely-inclined shafts having vertical and 110 horizontal adjustments, and a series of undercutting-saws mounted on an auxiliary shaft having similar adjustments, the two sets of saws located in substantially the same vertical plane and on opposite sides of the table 115 upon which the board to be dressed rests, whereby the board is held firmly between the two sets of saws, the whole supported upon a suitable frame-work, with mechanism for driving the same, substantially as shown and described. 120

In witness whereof I have hereunto set my hand this 6th day of July, 1886.

EDWIN M. BYRKIT.
